STEEL FRAME THRESHER SCREEN

William A. Holtzman, Peoria, Ill., assignor to
Hart-Carter Company, Peoria, Ill., a corpora-
tion of Delaware

Application October 22, 1941, Serial No. 416,036

4 Claims. (Cl. 189—36)

This invention relates to thresher screen frames such as are employed in grain threshers or combined harvester threshers.

Heretofore the frames of such screens have been commonly made of wood because this material, when of good quality, made a satisfactory frame for ordinary uses and could be readily repaired in the field by ordinary tools in the hands of farm mechanics. However, the growing use of combined harvester threshers with greatly increased harvester speeds and the stresses and strain of rapid transportation over rough ground, together with increased difficulties in getting proper quality lumber for frames, has indicated the need for stronger, stiffer and better-fitting thresher screens.

The particular object of this invention is to provide a structure for steel frame thresher screens which are strong and light and may be made up in a wide variety of accurate sizes from the same tools and which may be quickly and easily repaired by farm mechanics with ordinary tools.

Other objects and benefits will be disclosed in the following descriptions and drawings, in which:

Fig. 1 is a top plan view showing my new steel frame thresher screen;

Fig. 2 is a cross sectional view through an end section frame, as it would appear on the section lines 2—2 of Fig. 1;

Fig. 3 is another similar cross sectional view as it would appear on the section lines 3—3 of Fig. 1;

Fig. 4 is an enlarged perspective view of a steel reinforcement member, as will later be explained;

Fig. 5 is a broken, cross sectional, elevational view of the side frame showing the cross wires mounted in support notches, as would appear on the section line 5—5 of Fig. 1;

Fig. 6 is a broken side elevational view, partly in section, showing the center frame member and its mounting on the end members of the frame;

Fig. 7 is a cross sectional, elevational view of the center member showing a cross wire with adjustment crank, as would appear on the section line 7—7 of Fig. 1;

Fig. 8 is a broken underneath plan view of the frame corner with partial assembly shown in dotted outline, as will later be explained;

Fig. 9 is an upright section of the frame corner, as would appear on the line 9—9 of Fig. 8; and

Fig. 10 is a developed plan view of the end frame member, later to be explained.

Fig. 11 is a bottom plan view of the rail 16 as shown in Fig. 8 with flap extended; and

Fig. 12 is an elevational view of the rail 16 as shown in Fig. 11.

Now referring to the drawings, I designate the side rails of the thresher screen by the numeral 15. The end rails 16 are attached to the side rails with a corner reinforcement member 17, as will later be explained in greater detail.

Referring to Figs. 2 and 3, it will be observed that the end rail 16 is made in a general rectangular tubular section with top extending flanges 16a and 16b extending inwardly therefrom. It will be understood that the rails 15 are made in similar section, having inwardly extending flanges 15a and 15b. However, the side rails 15 have circular indentations 15n embossed downwardly in the top of the flanges to form pivot sockets for the slat wires 18, as clearly shown.

Any suitable means, such as a plate, may be placed over these pivot sockets to prevent the ends of the wires 18 from being displaced therefrom under normal operating conditions. Extending crosswise in the center of the frame is a

central rail made up of two sections 20 and 21, which may be of wood or other suitable material joined together by any suitable securing elements 22, such as screws, bolts, or the like as clearly shown in Fig. 7. This central rail may be fas-

tened to the frame by rivets 23 or the like extending through the sections 16a and 16b of the end rails, as clearly shown in Fig. 6. It will be appreciated that these rivets merely hold the bottom member 21, and the top section 20 may be

removed with an ordinary screw driver by removing the securing elements 22, whereupon the cross wires 18, having central cranks 18c, may be removed for repairs or replacements of the slats 19.

Referring to Figs. 4, 8, 9 and 10, it will be observed that the steel corner reinforcement member 17 is made with square corners in accurate square conformation. This reinforcement section is inserted in the hollow corner and, as will

be observed by a study of Figs. 4, 8, 9 and 10, the square corner section permits the rails 15 and 16 to be assembled with accurate square corners and with the holes 16h and 16h (Fig. 10) in alignment where they may be securely held by the

through rivets 24 (Figs. 8 and 9). It will be observed that the ends of the rails 15 and 16 are arranged to abut and overlap each other to effect a stiff, interlocked corner. I show in Fig. 10 the flat, developed plan view of the end rail 16, and

I wish to explain that the entire end of the rail

16, including the holes 16*h*, is cut with a die to effect accurate corner configuration of the rail. The side rails 15 have square ends and therefore holes corresponding with 16*h* are punched in accurate relationship with the square ends. By observing Figs. 8, 9 and 10 it will be seen how the rails are interconnected with the flat section 16*f* of the rail 16 extended as shown in dotted outline in Figs. 8 and 9. When assembled and riveted by the rivets 24 in accurate position the section 16*f* is folded around and beneath the rail 15, and the entire assembly spot-welded together, as indicated at spots marked "W," Fig. 8.

An analysis of this structure will show that the stiffener members 17 contribute largely to the stiffness of the assembly because they are inserted at the point of greatest strain, namely, the corners. However, in some installations, particularly with small screens, the stiffener member 17 may be left out, thus sacrificing strength for lightness.

It will be further observed that my rails are formed by bending operations which may be performed with any length of rail desired. Therefore, in order to make different size screens it is necessary to adjust only the length of the rails, and thus screens of various sizes may be constructed with the same set of tools.

It will also be observed that the cross-wire indentations 15*n* in the side rails 15 effectively prevent shifting of the extended flanges 15*a* and 15*b*, especially when these flanges are spot-welded together. Inwardly extending flanges 15*a*—15*b* and 16*a*—16*b* are important elements in my novel structure because they permit not only effective fastening together of the rails and the mounting of the cross wires 18 of the slats 19, but by their very nature permit field repairs with ordinary tools in the hands of a farm mechanic.

It will be appreciated that in high-speed, combined harvester threshers, the screens must fit accurately and firmly in position in order to effectively utilize the air blast and withstand severe service strains.

The application of my screen frame to a thresher screen or sieve, is set forth and claimed in my copending application on Steel frame thresher screen, Ser. No. 443,919, filed May 21, 1942. My said application sets forth also more in detail the slat adjusting mechanism generally referred to above.

It will be evident from the foregoing description that the side and end rail sections 15 and 16 are initially formed substantially of rectangular cross section, and are assembled with their respective flanges 15*a*, 15*b* and 16*a*, 16*b* extending inwardly of the frame, generally as illustrated in Fig. 8. The reinforcing member 17 has the arms thereof fitted into said rectangular rail sections, or the latter are formed therearound, and the rails are thus assembled with the rail 15 arranged with its extreme end in abutting endwise contact with the inside wall of the rectangular section of the end rail 16, in which relation the flanges 15*a*, 15*b* and 16*a*, 16*b* are interlapped, as shown in Figs. 8 and 9. In this relation the holes in the flanges of the rails 15 and 16 are in alignment, and the rivets 24 may be inserted therein and secure these flanges and the rails together. The

flap 16*f* which initially projects outward in a horizontal direction as shown in dotted lines in Fig. 9, is then wrapped around the rail 15, as shown in full lines therein, throughout the outer sides and bottom of the side rail section, to which it is secured, as by spot welding. Additional welds may be used to secure the other parts in their assembled relation, as indicated at W in Fig. 8.

Having thus described my invention, I now claim as new:

1. In a steel thresher screen, side and end rails formed in hollow rectangular sections with inwardly extending flanges, the rails having rivet holes near their ends through the flanges, the end rails being formed with folding flaps on the top flanges, the inside ends of the side rails being formed and arranged for abutting endwise contacts with the inside walls of the rectangular section of the end rails, the flanges being interlapped with the rivet holes in alignment when in exactly square sized relationship, rivets through the rivet holes, the flaps of the end rails being folded around the outside edges and bottoms of the rectangular sections of the side rails, and fastening means to hold the parts in square relationship.
2. In a steel thresher screen, side and end rails formed in hollow rectangular sections with inwardly extending flanges, the rails having rivet holes near their ends through the flanges, the end rails being formed with folding flaps on the top flanges, right angle corner reinforcement members fitting inside the ends of the rectangular rail sections, the inside ends of the side rails being formed and arranged for abutting endwise contacts with the inside walls of the rectangular section of the end rails, the flanges being interlapped with the rivet holes in alignment when in exactly square sized relationship, rivets through the rivet holes, the flaps of the end rails being folded around the outside edges and bottoms of the rectangular sections of the side rails, and spot-welding means to hold the parts in square relationship.
3. In a steel thresher screen, side and end rails formed in hollow rectangular sections with inwardly extending flanges, the rails having rivet holes near their ends through the flanges, the end rails being formed with folding flaps on the top flanges, the flanges being interlapped with the rivet holes in alignment when in exactly square sized relationship, and rivets through the rivet holes, the flaps of the end rails being folded around the outside edges and bottoms of the rectangular sections of the side rails.
4. In a steel thresher screen, side and end rails formed in hollow rectangular sections with inwardly extending flanges, the rails having rivet holes near their ends through the flanges, the end rails being formed with folding flaps on the top flanges, right angle corner reinforcement members fitting inside the ends of the rectangular rail sections, the flanges being interlapped with the rivet holes in alignment when in exactly square sized relationship, and rivets through the rivet holes, the flaps of the end rails being folded around the outside edges and bottoms of the rectangular sections of the side rails.

WILLIAM A. HOLTZMAN.
